UNITED STATES PATENT OFFICE.

HARRY PETRO RASMUSSEN, OF HUTCHINSON, KANSAS.

ACCORDION.

Application filed September 17, 1923. Serial No. 663,293.

To all whom it may concern:

Be it known that I, HARRY PETRO RASMUSSEN, a citizen of the United States, residing at Hutchinson, in the county of Reno 5 and State of Kansas, have invented certain new and useful Improvements in Accordions; and I do declare the following to be a full, clear, and exact description of the invention, such as will enable others skilled 10 in the art to which it appertains to make and use the same.

This invention relates to improvements in wind instruments and one object thereof is to provide a keyboard having a plurality of 15 rows of keys corresponding to an equal plurality of the strings of a manually fingered stringed instrument and adapted to be fingered with the left hand, for instance, in substantially the same manner as a violin, 20 viola, cello, or other instrument of the violin type, so that a musician familiar with stringed instruments, may readily adapt his knowledge to the fingering of a wind instrument embodying my invention.

Another object is to specifically adapt the invention to an accordion of the type in which the right hand is used to manipulate the bellows-operating portion of the instrument, while the left-hand portion of such instrument, 25 strapped to the musician's body, leaving his left hand free for unhampered fingering. In so adapting the invention to an accordion, I reverse the usual positions of the treble and bass keyboards and thus 30 provide for using the free left hand on the treble keyboard, and the bellows-operating right hand for the accompaniment. Thus, by the use of my invention, the treble keyboard is easily fingered by a stringed instrument 35 musician and only the fingering of the bass keyboard with the right hand, need be learned.

With the foregoing in view, the invention resides in the novel subject matter herein- 40 after described and claimed, the description being supplemented by the accompanying drawings.

Figure 1 is a perspective view showing an 45 accordion constructed in accordance with my invention.

Fig. 2 is a plan view of the treble keyboard at the left side of the instrument.

In the present disclosure of my invention, 50 an accordion 1 is shown, of the type embodying a movable, right hand, bellows-operating portion, and a stationary left-

hand portion, the latter being adapted to be strapped to the musician's body, leaving his left hand entirely free for fingering the treble keyboard 2, which is carried by said 60 stationary portion, while the right hand which operates the bellows is used for finger- 65 ing the bass keyboard 3 embodied in the above-named movable portion.

The keys of the treble keyboard 2 are dis- 70 posed in a plurality of closely spaced, vertically elongated rows adjacent the outer vertical edge of the stationary, left-hand portion of the instrument. The rows of 75 keys are preferably straight and the tops of all keys of said rows may or may not be dis- 80 posed in substantially the same plane, as de- 85 sired. These rows of keys correspond to the strings of a stringed instrument, and each row contains keys for at least one com- 90 plete chromatic octave. The keys produce tones which vary in pitch one row from an- 95 other, and in the present disclosure, I have shown an E-row 5, an A-row 6 one-fifth lower than said E-row, a D-row 7 one-fifth lower than said A-row, and a G-row 8 one- 100 fifth lower than said D-row. By arranging the keys in this or a similar manner, the fingering common to violins, mandolins and similar stringed instruments, may be used in connection with them, thus enabling a stringed instrument player to readily finger for any desired melody, with the hand which he is accustomed to using for the fingering operation. Thus, in order to enable a 105 stringed instrument player to play upon the accordion, it will be only necessary that he learn to finger the keyboard 3 for the accompaniment, with his right hand.

It will be seen from the foregoing, that I 110 have produced a distinct improvement in wind instruments and while the exact arrangement of keys shown in Fig. 2 is pref- 100 erable, it will be obvious that changes might well be made.

I claim:—

1. In a wind-instrument having means for producing tones, a keyboard comprising a plurality of tone-sounding finger buttons arranged in undeviating lines, said lines being disposed in laterally spaced relation and each containing buttons for at least one complete chromatic octave, said lines producing tones which vary in pitch one line from another.

2. In a wind instrument having means for producing tones, a keyboard comprising a

plurality of rows of keys, each row containing keys for at least one complete chromatic octave and each row being straight from end to end, said rows producing tones which

5 vary in pitch one row from another.

3. In a wind instrument having means for producing tones, a keyboard to be fingered with the left hand, said keyboard comprising a plurality of rows of keys corresponding to an equal plurality of the strings of a stringed instrument, each row containing keys for at least one complete chromatic octave, said rows being disposed in closely spaced relation, permitting fingering of the

10 keys thereof in a manner similar to the fingering of a stringed instrument, said rows producing tones which vary in pitch one row from another.

4. An accordion comprising a movable right-hand bellows-operating portion and a stationary left-hand portion, the latter being adapted to be strapped to the musician's body, leaving his left hand free; a bass keyboard carried by said right-hand, bellows-operating portion to be fingered with the right hand, and a treble keyboard carried by said stationary left-hand portion, said treble keyboard comprising a plurality of rows of keys corresponding to an equal plurality of the strings of a stringed instrument, each row containing keys for at least

one complete chromatic octave, said rows being disposed in closely spaced relation adjacent the outer vertical edge of said stationary left-hand portion, permitting fingering 35 of the keys of said rows in a manner similar to the fingering of a stringed instrument, said keys producing tones which vary in pitch one row from another.

5. An accordion comprising a movable 40 right-hand bellows-operating portion and a stationary left-hand portion, the latter being adapted to be strapped to the musician's body, leaving his left hand free; a bass keyboard carried by the right-hand bellows-operating portion to be fingered with the right hand, and a treble keyboard carried by said stationary left-hand portion, said treble keyboard comprising a plurality of tone-sounding 45 finger buttons arranged in undeviating lines in closely spaced relation adjacent the outer vertical edge of said stationary left-hand portion, permitting fingering of the buttons of said lines in a manner similar to the fingering of a stringed instrument, said 50 lines each containing buttons for at least one complete chromatic octave, said lines producing tones which vary in pitch one line from another.

In testimony whereof I have hereunto affixed my signature.

HARRY PETRO RASMUSSEN.
